Primary Examiner — T Chase Nelson*Assistant Examiner* — Jeff Lenard D Torres(74) Attorney, Agent, or Firm — McDonald Hopkins LLC(57) CLAIM

The ornamental design for a footwear sole as shown and described.

DESCRIPTION

The FIGURE view is a bottom plan view of a footwear sole showing my new design.

The broken lines show environmental structure that forms no part of the claimed design.

1 Claim, 1 Drawing Sheet(56)
